UNITED STATES PATENT OFFICE.

EDWARD G. PARKHURST, OF HARTFORD, CONN., ASSIGNOR TO HIMSELF
AND THE PRATT & WHITNEY COMPANY, OF SAME PLACE.

CARTRIDGE-FEED CASE FOR MACHINE-GUNS.

SPECIFICATION forming part of Letters Patent No. 229,007, dated June 22, 1880.

Application filed March 15, 1880. (No model.)

To all whom it may concern:

Be it known that I, EDWARD G. PARKHURST, of Hartford, in the county of Hartford and State of Connecticut, have invented certain new and useful Improvements in Mechanism for Feeding Cartridges to Machine-Guns; and I do hereby declare that the following is a full, clear, and exact description thereof, whereby a person skilled in the art can make and use the same, reference being had to the accompanying drawings, and to the letters of reference marked thereon.

Like letters in the figures indicate the same parts.

15 My invention relates to improvements in the construction of the boxes in which the cartridges for machine-guns are placed and transported, and in the receiving guide or hopper in which they are placed, and by which they 20 are carried to the lock and loading mechanism, whereby the placing of the cartridges in the gun is more rapidly and effectually accomplished.

25 The object of my invention is to save time and trouble in transferring the cartridges from the ammunition-cases to the gun when the arm is in use, and to place them with such accuracy of position in the gun that they will be sure to be properly fired.

30 In the accompanying drawings, Figure 1 is a side view of one of my improved cartridge-cases in the position of placing the cartridges in the receiver of the gun, the receiver being shown in section. Fig. 2 is a top or end view 35 of the improved cartridge case and receiver in the position shown in Fig. 1. Fig. 3 is a front view of the receiver.

40 A is a block, commonly of wood, bored full of holes for the reception of the cartridges up- 45 on one side, into which the cartridges are inserted ball foremost, so as to leave the heads nearly in the same plane.

B is a cover, made of tin-plate or other sheet metal, bent into the form shown in Fig. 2. 45 It has two longitudinal flanges, B', which enter into longitudinal grooves A' in the block A, so that the cover slides on lengthwise and is held in position by the flanges. This cover holds the cartridges in the block and prevents 50 their falling out in transportation.

D is the receiver. It is intended to be at-

tached to and form part of the gun and to be held firmly in position upon it, and is provided with channels E, leading directly to the chambers, from which the cartridge is pushed into the barrel by the lock mechanism. The channels E are constructed so as to hold the cartridges by the heads, the front of the channel being just of sufficient width to receive the body of the cartridge-shell and enlarged at the rear to form a groove for the projecting heads.

D' D' are flaring sides above the channels E, intended to guide the cover B to its proper seat on the receiver. They may be extended upward to any distance required to easily and quickly enter the cover of the cartridge-case between them and pass it down to its seat upon the top of the parts E', forming the sides of the channels. The back of D in the plane of the bottom of the channels is continued upward to the height of the flaring sides D' or a little above them.

The operation of my invention is as follows: The case A, B, with the cartridges contained within it, is taken in the hand, and the lower end of the cover placed against the back of the receiver D. The case is then passed downward until the cover is guided by the sides D' D' to its proper seat. The block A then continues to move downward with the contained cartridges, which pass into the channels E, the cover being retained in its seat upon the top of the channels. When the block passes below the cover all the cartridges are entered in the channels and the cover falls off. The cartridges are thus placed in the gun at one motion of the hand, carrying the block downward.

What I claim as my invention is—

1. The receiver D, provided with flaring sides and seat at the top of the channels for guiding and holding the cover B, substantially as described.

2. The combination of a sliding-top cartridge-case with a receiver provided with a seat for the cover of said case and with channels for the heads of the cartridges, substantially as described.

EDWARD G. PARKHURST.
